UNITED STATES PATENT OFFICE.

HENRY CASEBOLT, OF SAN FRANCISCO, CALIFORNIA.

SWITCH FOR ENDLESS-CABLE WAYS.

SPECIFICATION forming part of Letters Patent No. 241,299, dated May 10, 1881.

Application filed March 17, 1881. (No model.)

To all whom it may concern:

Be it known that I, HENRY CASEBOLT, of San Francisco, in the State of California, have invented certain Improvements in the Construction of Switches for Endless-Wire-Cable Railways; and I hereby declare the following to be a full, clear, and exact description thereof, reference being had to the accompanying drawings, making part of this specification, in which—

Figure 1 is a plan view, showing a switch on a cable-road. Fig. 2 is a longitudinal vertical section. Fig. 3 is a vertical cross-section on line $\alpha\alpha$ of Fig. 2. Fig. 4 is a view in detail.

On the class of railways wherein the cars are propelled by means of an endless cable moving in a tunnel and a gripe attached to the car moving through a slot in the top of the tunnel, whenever it is desired to switch cars from one track to another, the converging or diverging slots come together and form a triangular opening which is of such an area that vehicle-wheels, or the feet of men or horses, might pass through were not some means provided for closing such opening. It is desirable to have the cars as they pass operate the device for opening and closing the triangular opening.

The object of my invention is to provide a device which will close the opening at the switch, and which, by the passage of the car, will be made to force the covering away from the opening, and the covering will return to its place automatically.

My invention consists in a sliding plate mounted on curved rocking levers controlled by a counterpoise-weight, said plate having diagonal ends, whereby the gripe-shank forces the plate to one side as the car passes, and the counterpoise-weights return the plate to a position to cover the opening, as hereinafter described and claimed.

In order that those skilled in the art may make and use my invention, I will proceed to describe the manner in which I have carried it out.

In the said drawings, nn are the yokes supporting the tunnel, and a, a' , and b are the slots for the gripe-shank to move through. The meeting of these slots causes an opening, sss , triangular in shape, and which it is necessary to keep closed.

Below the opening sss is an angle-iron closing-plate, e , which slides from beneath an enlarged slot-iron, d , of such capacity as to allow e to recede until its edge is flush with d , thereby allowing a free and full passage for the gripe. The plate e rests upon the upper ends of bent rocking levers g, g , which have their bearings on a rock-shaft, i , which is journaled in boxes kk , bolted to transverse angle-iron supports oo , bolted to the yokes nn , as shown.

On the ends m of levers g are placed counterpoise-weights l , which, by their gravity, hold the plate e beneath the opening sss normally. It is necessary that the weights l should be overcome and the plate e be made to recede from the opening sss as a car approaches from either direction, and this I accomplish by means of a plate, f , longer than plate e , and bolted to it by means of countersunk bolts and intervening thimbles h , as seen in Fig. 4.

Toward its ends the plate f has its edges cut diagonally, as seen at 45 , and these diagonal lines cross the lines of the slots, as shown in dotted lines in Fig. 1.

As a car approaches plate e the shank of the gripe strikes the diagonal edge of plate f , and, pressing it to one side, overcomes the counterpoise l , tips the levers g, g , and throws the plate e into the position shown in Fig. 3, so the gripe can pass through the opening sss . As soon as the gripe passes on into one of the slots, the weight l brings down the short arms of the levers, and plate e is thrown beneath opening sss .

Having thus described my invention, what I claim as new, and desire to secure by Letters Patent, is—

1. In a switch for endless-cable ways, a movable covering-plate, e , in combination with an operating-plate, f , provided with diagonal ends located in the line of travel of the gripe, for the purpose specified.

2. The rocking levers g , rock-shaft i , counterpoise-weight l , and supporting-bars o , in combination with the movable plate e , operating-plate f , and slots a, a', b , all constructed and arranged as and for the purpose set forth.

HENRY CASEBOLT.
